United States Patent Office.

THOMAS M. FELL, OF NEW YORK, N. Y.

Letters Patent No. 60,709, dated January 1, 1867.

IMPROVED CYLINDRICAL AMALGAMATOR.

The Schedule referred to in these Letters Patent and making part of the same.

TO ALL WHOM IT MAY CONCERN:

Be it known that I, THOMAS M. FELL, mining engineer, of 26 Broadway, in the city, county, and State of New York, have invented, a new and improved Process of Amalgamation; and I do hereby declare that the following is a full and exact description thereof, reference being had to the accompanying drawings, and to the letters of reference marked thereon.

My said invention, called Fell's Cylindrical Amalgamator, consists as follows—

Figure 1 being a longitudinal vertical section.

Figure 2, a sectional elevation.

Figure 3, an end view.

A is a cylindrical wooden vessel, (but if preferred, it may be made of cast or boiler iron,) constructed of staves two and a half inches thick, tongued and grooved, and braced around its circumference with iron clamps or hoops, size preferred, two feet eight inches in diameter by ten feet long. B is a partition permanently fixed, which supports the steam and water pipes, holds the dash-board in position, forms a strong brace for the cylinder, and performs very essential service in facilitating the discharge of its contents. C is a cover or lid sliding in the grooves, C¹, and fastened by a catch; this lid may be left open or shut, at the discretion of the operator. ~~D, gudgeon or~~ bearings cast on and forming part of the plate E, to which the wooden heads of the cylinder are made fast by bolts and nuts. F, box-bearings bolted to the under side of the wooden frame G, resting on the ground or floor of the building. H H, driving vibrating cranks with bolts and nuts. I, crank-rod. K K, driving revolving cranks keyed to the driving-shaft. L M, common bearings or boxes. N, fast and loose pulleys. O, water pipe passing through one end of the cylinder and the centre of the gudgeon D. P, discharge-box, consisting of three valves opening and closing by action of the spindle marked 1, screw-box 2, and a handle (portable) not shown. What I call my "dash-board" or "suspender," is marked R, in which consists the essential novel feature and advantage of my amalgamator. Its position, when in action, is shown in fig. 2. It is made of wood two and a half inches thick, fitting the length between the partition B and one end of the cylinder, raised three-fourths to one inch from the bottom, the former height being sufficient for most descriptions of ore. For the purpose of warming the contents of the cylinder, which is found to assist the process of amalgamation, although I obtain practical results without this auxiliary, I pass a steam pipe, S, through the end of one of the plates E, and gudgeon D, to the other end-plate, then stop it with a plug, U, and connect it with the branch pipes, V, perforated with a few holes for the passage of condensed water; these steam pipes are made either to pass through the thickness of wood forming the dash-board, or on one side, which allows the same to be swung around on its axis formed by the pipe S in the plates E.

The operation of my machine is as follows: Motion being given to the cranks K K by the shaft L and the pulley N, by any convenient power, the cylinder is caused to oscillate or vibrate about twelve times per minute, which will be found in practice sufficiently fast. This vibratory motion is obtained by the difference in the two series of cranks, H H and K K, the latter being about one-third longer from the centre to the point of motion than the former, thereby permitting the cylinder to move around on its axis only, about one-third of its circumference, and then returning to its former position. The effect of this alternate motion is, that the entire charge, consisting of two hundred and fifty pounds of the pounded ore or material, which is the proper quantity for a machine of this size, with about thirty gallons, or six inches in height, of water, and mercury, say about fifty pounds, is made to pass in a narrow stream twice during every full stroke of the cranks H H, under the dash-board and through the space of three-fourths of an inch left between it and the bottom of the cylinder, the mercury rolling along leisurely, while the ore, by this peculiar sluice motion, is entirely suspended in the water without the aid of any mechanical stirrer or other similar contrivance whatever. Periodically, say at the end of forty minutes, by which time the gold or metallic silver has been completely absorbed, the top valve is opened and the contents allowed to pass out, after which the second or lower valve is opened, and finally the bottom or third valve. All the residuum is caught for an after treatment or washing, which, however, may be put back into the cylinder, as it will be found to be but few pounds' weight, so as to recover any stray pieces of amalgam. This sluicing motion is essentially a new and useful feature in the amalgamation of gold and silver with mercury. The entire charge, when lifted up above the ordinary water level on one side of the board, rushes by its own

gravity through the narrow pass or space to the other side, thereby accomplishing a thorough suspension of the auriferous material, (silica, sulphides, oxides, alumina, &c.) These particles so forcibly rub or abrade each other, that all atoms of precious metal adhering thereto (consequent upon every manner of grinding ores) will separate by trituration, and descend or drop into the bulk of mercury rolling on the bottom. At the same time small portions of mercury will likewise be suspended, which, coming in contact with the very minute scaly filaments of metal floating or held by cohesive attraction to small pieces of matrix, will readily dissolve the same by attrition of particles. It is obvious that the above-described amalgamator is susceptible of many modifications. The sluice motion may be had in a rotating cylinder with a succession of sluice-boards; but

What I claim as my invention, is—

1. The introduction of the alternating sluice or flood motion for obtaining entire suspension and trituration of the mass, accomplished by what we designate a dash or sluice-board, acting in connection with a vibrating or oscillating cylinder, substantially as above set forth, for the purpose of amalgamation of gold and silver ores.
2. I claim the introduction, for the purpose of amalgamation, of an oscillating or vibrating cylinder, to which I attach my dash or sluice-board, all substantially in the manner herein described.

THO. M. FELL.
